Primary Examiner — Carla Jobe Wright(57) **CLAIM**

We claim the ornamental design for a device skin, as shown and described.

DESCRIPTION

FIG. 1 is a front perspective view of a device skin; FIG. 2 is a back perspective view of the device skin; FIG. 3 is a back elevational view thereof; FIG. 4 is a front elevational view thereof; FIG. 5 is a right elevational view thereof; FIG. 6 is a left elevational view thereof; FIG. 7 is a top plan view thereof; and, FIG. 8 is a bottom plan view thereof.
The broken lines shown in FIG. 5 depict environment of the device skin and form no part of the claimed design.
